UNITED STATES PATENT OFFICE

166,558

MOLDED FOOD PRODUCT

Leo Peters, Evanston, Ill.

Application January 11, 1952, Serial No. 18,010

Term of patent 14 years

(Cl. D82—2)

To all whom it may concern:

Be it known that I, Leo Peters, a citizen of the United States, residing at Evanston, county of Cook, and State of Illinois, have invented a new, original, and ornamental Design for a Molded Food Product, of which the following is a specification, reference being had to the accompanying drawing, forming a part thereof, in which:

Fig. 1 is a side perspective view of a molded food product, showing my new design; Fig. 2 is an end view; Fig. 3 is a side elevational view; Fig. 4 is a top plan view; and Fig. 5 is a bottom plan view thereof.

I claim:

The ornamental design for a molded food product, as shown.

LEO PETERS.
